UNITED STATES PATENT OFFICE.

CHARLES BAYLY FRANKLIN, OF SPRINGFIELD, MASSACHUSETTS, ASSIGNOR TO
HENDEE MANUFACTURING COMPANY, OF SPRINGFIELD, MASSACHUSETTS, A
CORPORATION OF MASSACHUSETTS.

KICK-STARTER SUPPORT.

1,420,479.

Specification of Letters Patent. Patented June 20, 1922.

Application filed June 1, 1921. Serial No. 474,233.

To all whom it may concern:

Be it known that I, CHARLES BAYLY FRANKLIN, a subject of the King of Great Britain, residing at Springfield, in the county of Hampden, State of Massachusetts, have invented certain new and useful Improvements in Kick-Starters Supports, of which the following is a description, reference being had to the accompanying drawings and to the figures of reference marked thereon.

Heretofore the supporting structure for starting cranks of motorcycles has not been sufficiently rigid and strong. In prior constructions it has been the practice to support the starting crank by forming a bearing therefor in the wall of the transmission case carried by the cradle and to support the lower end of the seat-post from a cross frame carried behind the case by the side frames of the cradle. While this construction has been a distinct advance in frame construction, its principal objection lay in the fact that the casing wall did not provide a sufficiently strong bearing.

The principal object of this invention is to provide a strong and durable bearing for this kick starting crank by supporting it directly from the cradle.

Another feature of the invention resides in forming a special support adapted to be attached to the cradle, which support is formed with a bearing for the starting crank, and also with a means for connection with the lower end of the seat-post. This construction not only provides a sturdy bearing for the kick starter and for the seat-post, but also positions the kick starter substantially under the seat-post which is a more desirable location for securing an effective operation from the driving seat.

Still another feature of this invention resides in providing means for bolting this special frame or upright to the rear of the transmission casing whereby not only to form a firmer intersupport for these two members but also to provide a sure and positive means for determining the distance between the starting crank journal on which the starting sector is mounted and the projecting end of the transmission shaft on which the gear meshing with the sector is mounted.

A further feature of the invention resides

in providing a special support for the kick 55 starter constructed and arranged so that the machine may be equipped with a starter on either side thereof. The invention also contemplates utilizing this support if desired, as a bearing for the bell cranks for operating the brake mechanism.

These and other objects will in part be obvious and will in part be hereinafter more fully disclosed.

Referring more particularly to the accompanying drawing:

Figure 1 is a perspective view of the improved support, the transmission case being shown in dotted lines;

Fig. 2 is a perspective rear view of the 70 support;

Fig. 3 is a view similar to Fig. 1 of the support used when the machine is to be equipped with a starter on either side, and

Fig. 4 is a detached view of the support.

In general, the invention comprises a separate, comparatively short standard or upright, the base of which straddles the parallel side frames of the cradle being permanently attached thereto as by brazing. The 80 upper portion of the standard is formed as a hollow sleeve adapted to form a supporting seat for the lower end of the seat post which is brazed therein, while the intermediate portion of the standard is formed as a 85 laterally projecting bearing for the starting crank stud. The front of the upright is provided with a lug by which it may be bolted to the rear of the transmission case. In this manner, the case and the standard 90 mutually support each other while the distance between them and hence between the sector and transmission shaft journals is definitely fixed.

Regarding the drawing in detail, the main 95 frame or cradle includes the two parallel side members or tubes 1 and 2 on which the transmission case 3 shown in dotted lines is mounted as usual. Immediately to the rear of this case and supported by the side frames 100 is the short standard or support forming the subject matter of this invention. This support in the embodiment illustrated takes the form of a short upright 4 provided with an integral transverse base 5 straddling the 105 side tubes 1 and 2 and provided with bearings 6 and 7 adapted to be brazed or otherwise firmly connected to these side members

of the cradle. The upper portion 8 of the upright 4 is preferably formed as an open-ended sleeve 9 in which fits the lower end 10 of the seat post, being preferably brazed 5 therein. Intermediate the base 5 and the sleeve 8, the upright is formed with an integral lateral projection suitably shaped and bored to form a bearing for the stud or journal 12 on which the kick starter sector 10 13 and the pedal lever 14 are mounted as desired.

This sector and lever are preferably formed integral for this construction. The spring 15 is coiled about the journal and is 15 suitably attached to the support and sector at its opposite ends so as to normally swing the sector clear of the transmission gear journaled on the outside of the transmission case as shown in dotted lines in the drawing.

In order to rigidly interconnect the case and the upright, the latter is formed in front with an integral lug 16 bored vertically as at 17 to receive a bolt likewise passing 25 through a lug on the rear of the transmission case. By this means, the distance between the journals for the sector and the intermeshing transmission gear are accurately determined.

30 Figures 3 and 4 illustrate a slight modification of the bearing as arranged so that a machine can be equipped with a starter operable from either side of the machine. In this construction, the intermediate bearing is arranged symmetrically to project laterally on 35 both sides of the upright and is bored entirely through to receive, as desired, a long or short pin or stud.

Figure 3 shows the short pin used, in this 40 arrangement, as in Fig. 1, the sector and foot pedal are mounted on the same end of the pin. Fig. 4 shows the long pin 19 passing through the bearing. In this construction, the foot pedal 20 is attached to one end of the pin and the toothed sector is attached to 45 the other, so that the machine can be started from the left-hand side. Figures 3 and 4 also show the base of the upright formed with integral bearings 22 and 21 arranged 50 on the sleeves 23 and 24. These bearings are bored to receive a transverse rod 25 to the opposite ends of which are fixed cranks 26 and 27 connecting with the forward and rearward rods for operating the brake mechanism. Obviously, these bearings and the 55 rod 25 may be omitted if desired.

It will be obvious that minor changes in the details of construction and the arrangement of the parts may be made without departing from the spirit of the invention as 60 set forth in the appended claims.

Having thus described the invention, what I claim as new and desire to secure by Letters-Patent, is—

1. In a motorcycle, the combination with 65 the cradle and transmission case carried thereby, an upright supported by said cradle rearwardly of said case and provided with a bearing, a toothed sector, and kick-starter lever journaled in said bearing, said sector 70 adapted to mesh with a gear journaled in the transmission case.

2. In a motorcycle, the combination with 75 the cradle and a transmission case carried thereby, an upright supported by said cradle rearwardly of said case and provided with a bearing, means for connecting said upright to said case to hold the same in fixed relation thereto, a toothed sector and kick-starter lever journaled in said bearing, said 80 sector adapted to mesh with a gear journaled in said transmission case.

3. A kick-starter support for a motorcycle comprising an upright having a base adapted to be supported by the side frames 85 of the cradle, said upright being formed at its upper portion to support the lower end of the seat-post and also provided with a bearing for supporting the starting crank sector and foot lever.

4. A kick-starter support for a motorcycle comprising an upright having a base adapted to be carried by and permanently attached to the side frames of the cradle, said upright being formed with an upper open-ended sleeve adapted to receive the lower end 95 of the seat-post, and an intermediate bearing for the kick-starter sector and foot lever.

5. A kick-starter support for a motorcycle comprising an upright having a transverse 100 base provided with bearings adapted to be connected to the side frames of the cradle, said upright being formed at its upper portion to support the lower end of the seat-post and with a bearing for supporting the 105 starting crank sector and foot lever, said base bearings also being formed with additional bearings for supporting the brake operating control rods.

In testimony whereof, I affix my signature. 110

CHARLES BAYLY FRANKLIN.
